UNITED STATES PATENT OFFICE

2,646,268

COTTONSEED DELINTING APPARATUS

Robert L. Jackson, Lubbock, Tex.

Application May 28, 1949, Serial No. 95,909

4 Claims. (Cl. 263—34)

1

This invention relates to improvements in cottonseed delinting apparatus, more particularly to a cottonseed delinting apparatus which is compact and which may be readily charged and discharged, and which is designed to operate at various angles and which apparatus has a self-contained burner so as to furnish the proper heat to the delinting chamber by conduction.

Various cottonseed delinting apparatus have been proposed heretofore, but these for the most part were cumbersome and bulky, and utilized heating systems that required the heating of oil or other liquids, and the danger and trouble incident thereto.

In the present invention the delinting device is made of a single composite unit, which is self-contained and may be easily operated by a single operator, if desired, and which will delint cottonseed speedily and efficiently, and in a greater volume than similar size units now in general use.

An object of this invention is to provide a cottonseed delinting device that may be readily charged with seed and a halogen gas, heated quickly to the proper temperature and elevated in such manner as to discharge the entire seed content quickly and while in motion.

Another object of the invention is to provide a delinting machine that is mounted for rotation, whether in horizontal position or in an angular position, and which seed may be charged or discharged while the drum of the delinting apparatus is rotating.

A preferred manner of practicing my invention is shown in the accompanying drawings, in which:

Fig. 1 is a side elevation of the device with parts broken away, shortened, and shown in section to show the details of construction;

Fig. 2 is a plan view of the invention, with parts broken away and removed;

Fig. 3 is a sectional view taken on line 3—3 of Fig. 1, looking in the direction as indicated by the arrows;

Fig. 4 is a fragmentary elevational view of a fluid cylinder operated seed discharge door closer, with parts broken away and shown in section;

Fig. 5 is a sectional view of a modified form of a screw type seed discharge door closer;

Fig. 6 is an end elevational view, partly broken away, and partly in section, looking at the left end of the device as seen in Fig. 1;

Fig. 7 is a side elevation of a modified form of the device, partly broken away and in section to show the details of construction;

2

Fig. 8 is a cross section view taken along the line 8—8 of Fig. 7, looking in the direction indicated by the arrow;

Fig. 9 is an end elevational view, looking at the right hand end of the modified form of the invention shown in Fig. 7; and

Fig. 10 is a fragmentary view of the end section, on a somewhat enlarged scale, showing structural details of the support for the rear end of the rotatable drum, the driving means therefor, and the means by which halogen gas is introduced into the drum.

With more detailed reference to Figs. 1 to 6 inclusive of the drawings, illustrating one embodiment of the invention, the numeral 1 indicates a support member which has a pivot member 2 at the upper end for mounting frame 3 of the delinting apparatus. The opposite end of the frame 3 is supported by a hydraulic cylinder plunger 4 positioned within a hydraulic cylinder 5. The hydraulic cylinder is of sufficient length to raise the end of the frame 3, to which it is attached, a sufficient height to cause the dumping action of delinted seed therefrom, as will be described more fully hereinafter.

The frame 3 has uprights 6 at either end for the mounting of bearings to permit the rotation of the rotatable drum 10 on the frame. At the discharge end of the apparatus the bearing structure is indicated at 8, comprising suitable raceways enclosing ball bearings 15. Other conventional bearing structure may, of course, be provided in place of the particular structure described.

The charging end of the drum has attached thereto an annular flanged female packing member 47, secured about the opening in the drum by suitable bolts or other means. A member 9, forming the male portion of the packing gland, has welded thereto a tube 35 through which material is charged into the rotating drum. When the members 47 and 9 are assembled an annular cavity 37 is formed to receive a suitable packing material for this gland. For the purpose of compressing the packing material in the gland a grooved ring 48 is provided, which is secured to the rotating member 47 by means of stud bolts 54.

Ball bearings 7 are positioned in the groove of the ring 48, between the ring 48 and the stationary member 9, to permit the ring to rotate freely with the female member 47 of the packing gland.

Cross members 49 secured to the uprights 6 at the charging end of the apparatus support two rollers 45 below the axis of the rotatable

drum, and the roller 46 above the axis of the rotatable drum. The rollers 45 engage the outer surface of the member 47 to support the inlet end of the drum, and roller 46 also engages the member 47 as a guide to insure that drum 10 maintains the same relative position with the frame 3 at all times. Rollers 45 and 46 may be mounted on the cross members 49 by means of suitable brackets and antifriction bearings or other equivalent means.

It will be seen that in the structure just described the ball bearings 7 will take any axial thrust due to internal gas pressure in the rotatable drum. The discharge end of the drum 10 has an outstanding annular flange 11 thereon with brace members 12 extending outwardly therefrom parallel to the axis thereof. A cross member 13 has a shaft 14 extending outward in axial alignment with drum 10 and forms an axial mounting therefor. The shaft 14 is journaled in bearing 8 to enable the rotation of drum 10 by motor 16, which drives through a gear reduction unit 17 sprockets 18 and 19 and chain 20. The motor 16 is mounted on a frame 21 which is secured to frame 3, and is movable with frames 3 and 3'. The motor maintains driving relation with shaft 14 in any angular position to which the frame may be adjusted. The shaft 14 has mounted on the outer end thereof a cylinder 22, which is of the double acting type fluid cylinder. Pipes 23 and 24 are adapted to direct fluid through rotary coupling 25 to opposite ends of the cylinder to enable the selective operation of the piston P for longitudinal movement of rod 26 for opening and closing a discharge door 27. The discharge door 27 has a series of lugs 28 secured to an annular lip 29 so as to enable the connection of clevises 30 thereto. The other end of the clevises are connected to radial bars 31 which are pivotally connected to a hub 32. By the movement of the axial rod 26 by piston P, shown in Fig. 4 the discharge door 27 may be moved from full outline position as shown in Fig. 1 to the dash outline position or vice versa by the proper application of fluid pressure to the piston P.

The charging end of drum 10 has a charge opening 33 therein which is adapted to be closed by a closure 34 which fits in fluid tight relation with the end of the tube 35. A hand screw 36 is provided for applying pressure to closure 34.

As best seen in Fig. 1, the pipe 50 is welded to the tube 35, which pipe extends above the jacket surrounding the rotatable drum, and beyond the same and through the jacket surrounding the discharge door 27, for the purpose of discharging any excess halogen gas that might be in the drum 10 at the time for discharging the seeds from the drum. The pipe also extends through a slotted bracket 52 secured to the upper cross member 49. A rod 51 is also welded to the tube 35, extending downwardly therefrom through another bracket 52' secured to the lower cross member 49. The pipe 50, and rod 51, extending through the brackets 52' serve to prevent rotation of the member 9 and its associated parts, forming the charging opening of the rotatable drum, when the drum is rotated.

The pipe 50 is provided with a valve 57, for the purpose of closing off the passage of gas from the rotatable drum to the jacket enclosing the discharge door 27. A branch pipe 58 enters the pipe 50, as indicated in Fig. 1, below the valve 57, and this branch pipe is provided with a valve 59, the halogen gas may be ad-

mitted to the rotatable drum, and prevented from discharging into the casing surrounding the discharge door 27, or if the valve 59 is closed, the valve may be opened, any excess halogen gas in the rotatable drum at the time of discharging the cottonseed therefrom, will be discharged through the pipe 58 into the casing surrounding the discharge door 27.

As best seen in Fig. 6 of the drawings, the tube 35 forming the charging opening of the drum may be somewhat offset from the center of the member 9 to make available an area of said member for the application of one or more indicating instruments, such as the temperature indicator 56, or a pressure gauge, so that the conditions prevailing in the interior of the drum can be seen at all times.

A jacket having parts J and J' is secured to frame member 3' so as to enclose the drum 10 therein. A gas burner B is provided beneath drum 10 within jacket part J' so that the heat therefrom will be directed against the lower portion of the drum 10. It is preferable to have the burner B connected with a hose or other resilient coupling 37 so as to enable the burner to move with frame 3 when elevated by plunger 4 of the fluid cylinder 5. This fluid cylinder has an inlet in the lower end thereof to which a pipe 38 is connected for directing pressure from a suitable pump 39. Upon release of the fluid from the cylinder 5 by a valve V, the weight of the frame 3 will cause the cylinder to return to position, as shown in Fig. 1.

The drum 10 has baffles or ribs 40 around the inner periphery thereof forming in effect a tumbler so as to cause the agitation motion of the seed when the drum 10 is rotated. These ribs preferably extend the entire length of the cylinder and are parallel with the axis thereof so that upon the raising of the hydraulic plunger 4, the seed will move along the ribs and discharge through annular opening formed between discharge door 27 and the end of drum 10 when the door 27 is in open position, as shown in dash outline in Fig. 1.

A chute 41 is provided at the discharge end of drum 10 for directing the delinted cotton seed into a suitable conduit or container. A jacket surrounds the discharge door 27 which jacket has inter-fitting relation with the outturned flange 42 formed within inturned flange 43.

Vent pipes 44 are provided in the upper portion of jacket part J to enable the products of combustion to pass outward therefrom.

In the operation of the invention as described above, it will be seen that the cottonseed to be delinted is introduced into the rotatable drum 10 through the tubular member 35, which introduction takes place during the rotation of the drum, whereby the agitation of the seed by the ribs 40 about the interior of the drum will prevent the same from becoming overheated. The closure 34 is then clamped in fluid tight relation with the end of the tube 35, and the valve 57 is closed, after which the valve 59 may be opened to introduce halogen gas into the drum during the period of treatment of the seed.

At the termination of the treating process, the valve 59 is closed, and the valve 57 opened, to permit excess halogen gas to escape from the interior of the drum through the pipe 50 and into the chamber surrounding the discharge door 27. The device may then be elevated at its charging end by operation of the hydraulic cylinder 5, so that the drum slopes downwardly toward the dis-

5

charge end, and the discharge door 21 is then opened to permit the treated seed to be discharged through tube 41.

When desired the device may be elevated at the charging end by operation of the hydraulic cylinder 5, in order to facilitate the introduction of cottonseed into the rotatable drum. It will also be apparent that the treatment of the cottonseed can be carried out continuously, since a new supply of cottonseed can be introduced into the drum immediately after discharge of the previously treated seed, without turning off the heat, and with only a short period when the supply of halogen gas must be turned off during the actual charging and discharging operation.

A modified form of the invention is illustrated in Figs. 7 to 10, inclusive of the drawing, wherein a similar supporting frame structure to that described in connection with the embodiment described above is employed, comprising a bottom frame portion of generally rectangular configuration indicated by the numeral 60, with uprights 61 at either end. The uprights 61 at the charging end of the device are secured together by horizontal frame members 63 and 64, and the uprights at the opposite end of the frame are secured together by a horizontal frame member 65, which at its mid portion supports a bearing structure 66 for the rotatable drum 67.

The drum 67 is formed with a conical portion 68 at its open end, which rests upon rollers 70 supported on the lower frame member 63, for rotation thereon. An additional roller 71 is supported on the upper frame member 64, which serves as a guide to maintain the drum in the same relative position with the frame at all times.

The closed end of the drum, indicated at 73 is provided exteriorly with stiffening flanges 75, which serve to form a rigid structure capable of withstanding the pressure of gas in the drum during the treatment of seed therein. The flanges 75 also bear against the vertical surface of the bearing 66, as indicated at 76, in Fig. 10, thus enabling the structure to withstand relatively high thrust in the direction of the bearing 66.

The hollow shaft 78, upon which a sprocket wheel 79 is secured, extends through the bearing 66, and is attached to the closed end of the drum, as best seen in Fig. 10. The shaft 78 has an annular flange at its outer end, indicated at 80, and a male member 81 of a packing gland is secured to the flange 81 by bolts 83, for compressing packing material into the cavity 84 of the packing gland. Through the power shaft 78 and the packing gland extends a pipe 86 opening into the rotatable drum, for the purpose of introducing halogen gas into the interior of the drum.

A charging and discharging opening is provided at the conical end of the drum, which opening is closed by a hinged closure 88, clamped in fluid tight relation to the opening by a hand screw 89.

The rotatable drum 67 is enclosed in a jacket structure having upper and lower parts K and K' respectively, the upper part K being provided with pipes 90, for the purpose of conducting away the products of combustion produced by a burner 92 located beneath the rotatable drum. The gas burner 92 is preferably connected to a source of fuel by a hose 94, to permit the burner to move with the frame when the same is elevated.

A motor M suitably supported by the frame and movable therewith, drives the sprocket 79 through chain 98 to rotate the drum in a manner similar to that pointed out in connection with

6

the previously described embodiment of the invention.

One or more indicating instruments, such as a temperature indicator 96, seen in Fig. 8, may be positioned on the closed end 73 of the drum 67 for determining the conditions within the drum. The instruments applied in this manner can be positioned close to the axis of the drum to facilitate reading the same while the drum is rotating.

The modified form of the invention described above is operated in a very similar manner to that previously described, except that the charging and discharging operation takes place through the single opening in the rotatable drum at the conical end of the same. The same arrangement of hydraulic jacks as previously described may be applied to the modified form of the invention at the end of the frame which supports the closed end of the drum, and the frame may be pivoted at the opposite end to the supporting structure, to permit the device to be tilted to discharge the contents of the drum. The burner 92 can be left on during the charging and discharging of the drum, keeping the drum in rotation, to assure the thorough agitation of the seed.

Having thus described the invention, I claim:

1. In a device for delinting cottonseed a base, means pivotally connecting said base with a frame member, a jacket surrounding said frame and forming a furnace compartment, a vent pipe connected with said furnace compartment for venting the products of combustion therefrom, means journaling a tumbler within said furnace compartment, power means for rotating said tumbler, an inlet opening formed in an end of said tumbler for charging said tumbler with cottonseed while rotating, means forming a quick opening closure for said inlet opening, a discharge opening formed in the opposite end of said tumbler, means forming a closure at said opposite end of said tumbler, toggle means for effecting a sealing action between said closure and said tumbler while said tumbler is rotating, and heating means within said furnace compartment for heating said tumbler while said tumbler is rotating.

2. In a device for delinting cottonseed, a base, a frame, means pivotally connecting said base with said frame, a jacket mounted on said frame and forming a furnace compartment, a vent opening formed in said jacket for venting products of combustion therefrom, a drum, bearing means journaling said drum within said furnace compartment, an inlet opening formed in an end of said drum to enable the charging of said drum with cottonseed while said drum is rotating, power means mounted on said frame and connected to said drum in driving relation thereto, closure means for closing said inlet opening in positive pressure tight relation, a discharge opening formed in the end of said drum opposite said inlet opening, closure means for closing said discharge opening in positive pressure tight relation, means for operating each of said closure means while said drum is rotating, heating means within said furnace compartment for heating said drum, a visually readable temperature indicator means in an end of said drum for indicating the temperature within said drum, means for directing a halogen gas under pressure through an end of said drum into said drum, and means for elevating said drum while rotating.

3. In a device for delinting cottonseed, a base, a drum pivotally connected to the base and hav-

75

ing a conical end portion, an opening formed in said conical end for passage of cottonseed, closure means for closing said opening in said drum in pressure tight relation, means journaling said drum for rotation, power means connected to said drum in driving relation, a jacket mounted about said drum and forming a furnace chamber, heating means in the chamber positioned beneath said drum so as to position it in a longitudinally separated relation to the opening in said conical end of said drum, conduit means for introducing a halogen gas into said drum while said drum is rotating, and means for tilting said drum relative to said base while said drum is rotating in order to discharge the delinted seed and the combustible lint therefrom to a point exterior of said furnace chamber.

4. In a device for delinting cottonseed, a base, a drum pivotally connected to the base and having a conical end portion, a single opening formed in the conical end of said drum for the introduction of the raw cottonseed and the removal of delinted cottonseed after treatment, closure means for closing said opening in said drum in pressure tight relation, means journaling said drum for rotation, power means connected to said drum in driving relation, a jacket mounted about said

drum and forming a furnace chamber, heating means in the chamber positioned beneath said drum so as to position it in a longitudinally separated relation to the opening in said conical end of said drum, conduit means for introducing a halogen gas into said drum while said drum is rotating, the end of the drum opposite the conical end of the drum having a relatively small opening formed therein for introduction of said halogen gas, and means for tilting said drum relative to said base while said drum is rotating in order to discharge the delinted seed and the combustible lint to a point exterior of said furnace chamber.
